UNITED STATES PATENT OFFICE.

HENRY TAYLOR, OF CHICAGO, ILLINOIS.

DESIGN FOR A BABY-SPOON.

45,031.

Specification for Design.

Patented Dec. 9, 1913.

Application filed July 14, 1913. Serial No. 779,057. Term of patent 14 years.

To all whom it may concern:

Be it known that I, HENRY TAYLOR, a citizen of the United States, residing at Chicago, in the county of Cook and State of Illinois, have invented a new, original, and ornamental Design for Baby-Spoons, of which the following is a specification, reference being had to the accompanying drawing, forming part thereof.

Figure 1 is a perspective view of a baby spoon showing my new design. Fig. 2 is a top view.

I claim;

The ornamental design for a baby spoon, as shown.

HENRY TAYLOR.

Witnesses:

A. R. TAYLOR,
JAMES SHANNON.
